UNITED STATES PATENT OFFICE

150,509

DESIGN FOR A CARD FOR ARTIFICIAL TEETH OR SIMILAR ARTICLE

Simon Myerson, Brookline, Mass.

Application November 20, 1946, Serial No. 134,959

Term of patent 14 years

(Cl. D24—1)

To all whom it may concern:

Be it known that I, Simon Myerson, a citizen of the United States of America, residing at Brookline, in the county of Norfolk and Commonwealth of Massachusetts, have invented a new, original, and ornamental Design for a Card for Artificial Teeth or Similar Article, of which the following is a specification, reference being had to the accompanying drawing, forming a part thereof.

Fig. 1 is a top plan view of a card for artificial teeth or similar article, showing my new design;

Fig. 2 is an end elevation looking from right to left at Fig. 1;

Fig. 3 is a front elevation; and

Fig. 4 is a rear elevation.

I claim:

The ornamental design for a card for artificial teeth or similar article, substantially as shown.

SIMON MYERSON.
